UNITED STATES PATENT OFFICE.

HOWARD H. WIXON, OF CHICAGO, ILLINOIS, ASSIGNOR TO STROMBERG MOTOR DEVICES COMPANY, OF CHICAGO, ILLINOIS, A CORPORATION OF ILLINOIS.

MAGNETO-MACHINE.

1,176,805.

Specification of Letters Patent. Patented Mar. 28, 1910.

Original application filed March 4, 1910, Serial No. 547,190. Divided and this application filed December 17, 1910. Serial No. 597,741.

To all whom it may concern:

Be it known that I, HOWARD H. WIXON, a citizen of the United States, residing at Chicago, in the county of Cook and State of Illinois, having invented a certain new and useful Improvement in Magneto-Machines, of which the following is a full, clear, concise, and exact description, reference being had to the accompanying drawings, forming a part of this specification.

My invention relates to electric generators and its object is to provide such a device in which the various parts are arranged with great compactness, presenting a structure occupying a comparatively small amount of space without sacrificing anything in the line of efficiency, thereby securing many mechanical and electrical advantages.

The main feature of my invention is the provision of a stationary induction winding, having both primary and secondary coils.

Other features will be readily understood by consideration of the structure shown in the accompanying drawings, in which—

Figure 1 is a longitudinal sectional view and Fig. 2 is a transverse sectional view taken approximately on the plane of the line 2—2 of Fig. 1 and looking in the direction indicated by the arrows.

This case is divisional from my copending application Serial #547190 filed March 4, 1910.

Referring to the drawings, the main framework of the machine comprises a non-magnetic base portion 1, a pair of magnetic side portions 2, 2, a non-magnetic top portion 3, and supporting end plates 4 and 5, all held together in some suitable manner, for instance, by means of screws 6, 6. The permanent magnets 7, 7 are in good magnetic contact with the side pieces 2, and, extending upwardly, embrace some of the working parts of the machine, as is usual in the art. The main framework thus described has the central cylindrical bore or space 8, the sides of which form the polar faces 9, 9. In this cylindrical space within the framework is arranged a stationary induction winding 10, comprising the inner or primary coil 11 and the outer or secondary coil 12. Suitable insulation separates the coils from each other and also surrounds the out-

side of the coils, as indicated cross sectionally in Fig. 1. This induction winding is a unitary part which may be readily inserted in place in the magneto and as readily withdrawn therefrom, after the other parts located in the cylindrical spacing have been removed, as will hereinafter appear. The cylindrical ridge 13 on the outside of the winding is just sufficiently smaller in diameter than the space in the framework to permit the winding being inserted within the framework and held stationarily therein. In order to properly guide the winding in place when it is inserted within the framework of the magneto, suitable guiding means is provided, which, in the specific instance shown, consists of a lug 14, carried by the winding, and cooperating groove 15, provided at a suitable point on the framework within the cylindrical space, as clearly illustrated in Fig. 2. As a further locking means for the winding when in place, a spring pressed lug 16 supported in the framework by the screw threaded tube 17 is adapted to enter a recess 18 in the peripheral ridge of the winding. Upon withdrawal of the winding, the yielding lug 16 will be forced out of the recess. By thus providing guiding and locking means for the winding, it will always be possible to place the winding on the machine in exactly the same position. This is important when it is considered that upon the outside of the winding are located the terminals which are intended to engage certain contact members, as will be described subsequently, mounted at certain points on the machine. In order that the exposed terminals of the coils of the induction winding may register with the contacts carried by the framework, it is, of course, necessary that the position of the winding on the magneto be always the same with respect to the contacts. This sameness of position is insured by some such suitable guiding and locking means as above described.

Passing axially through the winding is the armature shaft 19, rotatably supported in bearings 20 and 21. The bearing 20 is carried by the supplementary end plate 22, screwed to the framework of the machine by means of screws 23 and the bearing 21 is mounted in the support 23, which is clamped

between the end plate 5 and the framework of the machine, as shown in the drawings. Anti-friction rollers 24, 24 work in the bearings 20 and 21. A pair of segmental inductor members 25 and 26 are screwed to the armature shaft at opposite ends of the winding. In the particular instance illustrated, the armature is screw-threaded at 27 and 28, and the inductor members are mounted on these screw-threaded portions, set screws 29 and 30 being provided on the inductor members to prevent accidental disarrangement of the polar extensions after they have been fastened in position on the armature shaft. Any other approved means of securing these inductor members to the armature shaft may be obviously employed, although the screw-threaded arrangement between the parts has the advantage of readily permitting axial as well as radial adjustment of the inductor members on the armature shaft. The inductor members, as well as the armature shaft are of magnetic material—at least that portion of the armature shaft which is included between the inductor members. It will therefore be seen that the armature shaft constitutes a rotatable magnetic core for the stationary induction winding. The angular position of the inductor members 25 and 26 on the armature shaft is such that they lie substantially diametrically opposite, as indicated in Fig. 1. In order to provide a large surface on faces of the inductor members, I preferably form the latter substantially as shown in Fig. 1, from which it will be seen that the inductor members are provided with axial elongations 31 and 32, respectively, these elongations project into spaces 33 formed between the winding and the surrounding surface of the main framework. By this arrangement the length of the machine is reduced, since, if the elongations of the inductor members projected outwardly away from each other, it would be necessary to lengthen the pole pieces accordingly, or else materially reduce the length of the induction winding, and thus reduce the efficiency of the machine.

The operation of the machine thus far described will be apparent to those skilled in the art. As the armature is rotated or oscillated, the magnetic flux of the field will be periodically short circuited through the winding, first in the one direction and then in the reverse direction. This short circuiting of the flux takes place when the inductor members are moving opposite the pole pieces, as indicated in Fig. 2, where the polar extension 26 is shown in a position 90° from the position indicated in Fig. 1. When the armature is in the position shown in Fig. 2, the magnetic flux will pass, (assuming the poles of the magnets as indicated by N and S,) from the north pole piece, in the induct-

tor member 25, through the winding in a direction away from the observer, returning by way of the inductor member 26 to the opposite pole piece. When the armature is in a position 180° from that indicated in Fig. 2, the magnetic flux will be reversed through the stationary winding, passing from the north pole piece into the inductor member 26, through the armature in a direction toward the observer, and returning through the polar extension 25 into the south pole piece.

When the inductor is set in rotation, an electromotive force is induced in the winding by the action of the field magnet. If now the primary coil is short circuited, the current flowing therethrough generates lines of magnetic force which largely neutralizes the existing magnetic field—that is, they force back or oppose a change of magnetism through the coil. As soon as the circuit in the primary is broken, the counteraction of the generated opposing flux ceases. Owing to the change which thereby instantaneously arises in the number of the lines of force passing through the secondary coil from the field magnets, the potential rises so high in the secondary coil that a spark is produced across the spark plug to ignite the explosive mixture in the engine cylinder.

The wire in the primary coil is comparatively coarse, and comprises comparatively few turns, while the wire constituting the secondary coil is comparatively fine and comprises a comparatively large number of turns, in order that the electromotive force generated in the secondary coil may be sufficiently high to cause sparking at the spark plugs of the engine cylinders. This is a matter of mere mathematical calculation to those skilled in the art, and no further explanation is necessary here on that point. The flux-carrying portion of the armature shaft is laminated at 34 in order to obviate or reduce to a minimum the eddy currents set up by the flux variations. This avoids undue heating of the armature metal and consequent waste of energy. The laminations lie, of course, in the plane of the inductor members of the armature, as indicated in the drawings. In order to sacrifice nothing of the rigidity of the armature shaft, only the major portion of the latter is laminated, the laminations 34 being secured in the cut-away portion 35. The armature shaft 19 has an extension 36, to which is rigidly secured the yoke 37, having at its opposite ends a pair of rollers 38 and 39. These rollers are insulated from the yoke, as clearly shown in Fig. 1. The yoke constitutes the movable contact member of an interrupter when the device is used for sparking purposes, this interrupter being shown and described in detail in my copending application Serial

#580,717, filed Sept. 6th 1910, that case being divisional from my copending application Serial #547,190, filed March 4th 1910. Suffice it in this description to say that the rollers 38 and 39 coöperate with movable contact springs 40 and 41 associated with stationary contacts (not shown) to break the primary circuit of an ignition system periodically.

10 When the device of my invention is used for ignition purposes, it is necessary that some sort of a "distributer" be employed when a multi-cylinder engine is associated therewith. The distributer illustrated in 15 the drawings comprises the subject matter of my copending application Serial #580,718, filed Sept. 6th, 1910, which case is also divisional from my copending application Serial #547,190, filed March 4th, 1910. In 20 this description suffice it to say that a plurality of contacts are stationarily mounted in the insulating casing 42, secured to the end plate 5 by means of screws 43. The contacts are individually connected with the 25 respective spark plugs by means of suitable leads. An auxiliary shaft 44 is mounted in the bearings 45 and 46, set into end plates 4 and 5, respectively, anti-friction balls 47, 47 being provided, and carries the gear 48 30 incased between the end plate 4 and supplementary end plate 22. This gear meshes with the pinion 49 secured upon the main shaft 19. The auxiliary shaft 44 beyond the bearing 46, carries the insulating block 50, 35 which operates in a circular pocket 51 in the casing 42, this pocket being covered by a mica plate 52. The insulating block 50 carries the contact member 53, which is adapted to contact successively with the rotary contacts, all as shown and described in detail 40 in my copending application last referred to. The insulating block 50 also carries a spark electrode 54, which is spaced from a metallic point 55 on the auxiliary shaft to 45 form a spark gap, which is described in my copending application just referred to as a "combined safety and testing spark gap" the auxiliary shaft 44 is provided with a central insulating portion 56 and the parts just referred to are connected in circuit with the 50 windings of the stationary induction coil by means of the ring 57 and plungers 58 and 59, the pin 60 connecting the plunger 58 with the metallic part of the auxiliary shaft. 55 The plunger 59 is connected with one terminal of the secondary coil by contacting with the end of the coil which is run out to the surface, as indicated by the conductor 61, the other end of this coil being connected 60 with the machine frame. The same general construction is employed in connecting one terminal of the primary winding with the plug in the bottom part 1. Insulating block 62, which is mounted into part 3 of the gen-

eral framework and through which the auxiliary shaft passes, and in which the plungers 58 and 59 are mounted, is provided with a connecting arrangement 63, which leads to the primary coil, this arrangement comprising the stems 64 and 65 and the spring 70 66, all as shown in Fig. 2.

I claim as new and desire to secure by Letters Patent:—

1. A magneto-generator comprising, in combination, a plurality of permanent magnets, a pair of pole-pieces in contact with said magnets, said pole-pieces having their polar faces curved in the arc of a circle, a stationary generator winding arranged within the space between the pole-pieces, and means for guiding said winding into a predetermined position between the pole-pieces. 75

2. A magneto-generator comprising, in combination, a plurality of permanent magnets, a pair of pole-pieces in contact with said magnets, said pole-pieces having their polar faces curved in the arc of a circle, a stationary generator winding arranged within the space between the pole-pieces, and a latch for securing said winding 85 against disarrangement when in position between said pole-pieces, said latch permitting ready removal of the winding. 90

3. In a magneto-generator, the combination of a field-frame, a stationary winding 95 arranged axially within said field-frame, a rotatable armature shaft passing through said winding to constitute the core thereof, the core-portion of the armature shaft having a transverse slot filled with laminations, 100 and an inductor member removably secured to said shaft at either end of the winding for reversing the magnetic flux therethrough as the shaft is rotated.

4. In a magneto generator, a cylindrical 105 magnetic armature shaft having a transverse slot filled with coextensive laminations.

5. In a magneto-generator, the combination of a field-frame, a stationary winding 110 arranged axially within said field-frame, and a rotatable armature for reversing the magnetic flux through said winding, said armature having a slot filled with laminations which pass through said winding. 115

6. In a magneto-generator for ignition purposes, the combination of a non-magnetic base-portion, a pair of magnetic side- 120 portions secured to said base-portion and forming pole-pieces, a non-magnetic top-portion secured to said pole-pieces and provided with an opening, said four portions constituting a hollow framework, magnets in contact with said pole-pieces, a stationary induction-winding arranged within said framework, an unwound armature rotatable within said framework for reversing the magnetic flux through said winding, an in- 125

sulating block extending into the opening of said top-portion, a rotatable shaft passing through said block, and a contact member mounted on said block for making electrical connection with a lead connected to said winding and said rotatable shaft.

In witness whereof, I hereunto subscribe

my name this 13th day of December, A. D.
1910.

HOWARD H. WIXON.
